CONCENTRATOR.

1,397,749.

Specification of Letters Patent.

Patented Nov. 22, 1921.

Application filed December 29, 1917. Serial No. 209,404.

To all whom it may concern:

Be it known that I, ALVA W. TYLER, a citizen of the United States, residing at Los Angeles, in the county of Los Angeles and State of California, have invented a new and useful Concentrator, of which the following is a specification.

This invention relates to concentrators of the type in which a table is vibrated for producing concentration of dry ores.

It is well known that practically all ore concentrating tables require certain movements given them in order to obtain stratification of the material being concentrated and travel of the material in a certain definite direction over the table surface so that the material of different gravities will discharge from the table at different places. The movements of the material are usually

accomplished by causing the table to "throw" along a certain path or line of movement by means of a "quick return" mechanism or so termed "head motion." This motion carries the material forward relatively slowly on the forward stroke, due to the friction between the material and the table surface, and on the return stroke the frictional resistance is overcome by the inertia of the forward moving material during the quick return of the table surface. The "quick return" demands relatively high consumption of power and is the cause of rapid destruction of the concentrator.

An object of this invention is to avoid frictional resistance of the material on the table on the return stroke thereof so as to reduce power consumption to a minimum.

Another object is to effect the same rate of travel of the table in both directions and to begin the strokes with a gradual acceleration and to end the strokes with a gradual retardation so as to prolong the useful life of the concentrator.

Another object is to make provision for moving the table in different paths of travel on its forward and back strokes so that at some part of the stroke the body of ore will be spaced from the table surface.

Another object is to provide a motion of the concentrator table such as will enable the ore to travel over the table when the table is aslant upward toward the discharge end so as to maximize the concentrating effect of the table movement on the ore.

Other objects are simplicity of construction and the production of such movement of the concentrator table as is capable of effecting rapid stratification and concentration of the material, with a relatively high efficiency due to simplicity of the motion mechanism and low cost of operation and up-keep.

The accompanying drawings illustrate the invention:

Figure 1 is a side elevation of a concentrator equipped with the invention.

Fig. 2 is an enlarged fragmental plan view, partly in section, of the table vibrating mechanism shown in Fig. 1.

Fig. 3 is an elevation, partly in section, from line x^3-x^3 , Fig. 2, the cover plate of the cam housing being omitted for clearness of illustration.

Fig. 4 is an elevation, partly in section, from line x^4-x^4 , Fig. 2, the shaft shoulder and cover plate of the cam housing being omitted for clearness of illustration.

Fig. 5 is a view of the shaft at the left end of Fig. 2, detached, the sprocket wheel, cam and pulley being assembled on said shaft.

Fig. 6 is an enlarged detail of the cam adjusting device.

Figs. 7 to 10 inclusive are diagrammatic views illustrating the paths of movement of the table occurring when the horizontal and vertical throw cams are set apart forty-five, ninety, zero and three hundred and fifteen degrees of angular measurement respectively.

Fig. 11 is a plan view of Fig. 1 omitting the blower, a portion of the table top being broken away.

Fig. 12 is a longitudinal section on the irregular line indicated by $x^{12}-x^{12}$, Fig. 11. Arrows indicate the paths of the air currents and the treated material.

Fig. 13 is an enlarged transverse section on the line indicated by $x^{13}-x^{13}$, Fig. 11, the table being shown tilted toward its discharge side. Arrows indicate the paths of the air currents and the treated material.

Fig. 14 is a transverse section through two of the riffles of the table, the material being treated being shown and the direction of transverse flow of the material and the paths of the air currents being indicated by arrows.

A concentrator frame is shown at 1 and the table therefor at 2. Air is supplied to the table by a blower 3 or other suitable air pumping device. The detailed construction of the concentrator table need not be shown and described herein since any suitable construction may be employed. The concentrator table illustrated in Figs. 1 and 11 to 13 inclusive is analogous to that disclosed by me in Letters Patent No. 1,262,603, granted April 9th, 1918.

The concentrator table 2 is hinged near opposite ends at 4 to a horizontally disposed vibratory arm 5 which may be adjustably connected as at 6 to the table 2 for purposes of regulating the transverse inclination of the table. The adjustable connection 6 need not be described in detail herein since it may be of any well known construction.

20 The frame is pivoted at 7 to a base 8 and tilting of the table lengthwise is effected by means of a vertical screw 9 engaging the frame, there being a bolt 10 to lock the frame in adjusted position on the base.

25 The arm 5 is connected with the frame 1 by vertical-motion eccentric devices and horizontal-motion eccentric devices so that the arm, and with it the table, may be moved endwise and up and down. One end of the 30 arm 5 may be provided with both vertical and horizontal-motion eccentric devices and the other end of the arm may be normally connected with the frame in any well known manner, but I have shown it connected by 35 vertical-motion eccentric devices. The eccentric devices will now be described in detail. The arm 5 is furcated at its opposite ends to form housings for the eccentrics and the furcations at one end of the arm are 40 provided in their chambers 11 with eccentric straps 12 in which rotate eccentrics 13.

45 Preferably antifriction bearings 14 will be interposed between the straps 12 and eccentrics 13. The eccentrics 13 may be constructed in any suitable manner and in the instance shown in the drawings said eccentrics comprise collars 14' mounted on hubs 15 which may be integral with a shaft 16 extending transversely of the table 2 and 50 rotatively mounted in a bearing 17 of the concentrator frame 1.

The furcations at the other end of the arm 5 are provided with chambers 18 in one of which are eccentric straps 19, 20 and in the 55 other of which are eccentric straps 21, 22. Rotatively mounted in the eccentric straps 19, 20, 21, 22 are eccentrics 23, 24, 25, 26 respectively, and preferably antifriction bearings 27 are interposed between the straps 60 and eccentrics. The eccentrics 23 to 26 may be constructed the same as described above for the eccentrics 13.

65 The eccentric 23 is partly formed integral with a shaft 28 which extends transversely of the table 2 and is provided with a

sprocket wheel 29 operatively connected by a sprocket chain 30 or otherwise with a sprocket wheel 31 on the shaft 16.

The eccentrics 24, 25 are partly formed integral with a sleeve or hollow shaft 32 which surrounds the middle of the reduced portion of the shaft 28 between the eccentrics 23 and 26. This sleeve is provided at one end with an internal conical seat 33 to fit a conical shoulder 34 on the shaft 28. 70 The sleeve 32 is provided with shoulders 35, in this case formed separate from the sleeve, bearing against the inner faces of the furcations of the arm 5 so as to prevent relative movement between the sleeve 32 and said arm and to exclude dust from the bearings.

75 The eccentric 26 is partly formed integral with a sleeve 36 which is rotatively mounted in a bearing 37 of the concentrator frame 1. This sleeve 36 surrounds the reduced portion of the shaft 28 and said reduced portion projects beyond the outer end of the sleeve 36 and is screw-threaded at its end 80 to receive a nut 38. When the nut 38 is tightened against the sleeve 36 it forces the sleeve 36 against the sleeve 32 to hold the sleeve 32 with its seat 33 tight against the shoulder 34. The reduced portion of the shaft 28 is provided with means such as a 85 pin 39 engaging a slot 40 in the sleeve 36 to hold said sleeve and the shaft against relative turning, thus to hold the eccentrics 23 and 26 against relative turning. These eccentrics 23 and 26 are in corresponding positions circumferentially of the shaft and the eccentrics 24, 25 are also in corresponding positions circumferentially of the shaft and in different positions than the eccentrics 23, 26. 95

100 The positions of the eccentrics 24, 25 may be adjusted relative to those of the eccentrics 23, 26 and for this purpose the sleeve 32 (see Fig. 6) is provided with a collar 41 having an arm 42, there being means such as a set screw 43 to hold the collar against 105 turning relative to the shaft. The standard 43' is provided with a disk 44 which may be graduated as indicated at 45 and by loosening the nut 38 the arm 42 and disk 44 may be turned relative to one another so as to produce relative adjustment between the eccentrics 24, 25 and the eccentrics 23, 26.

110 When the desired adjustment has been made the nut 38 will be tightened so that the adjustment will be maintained. The graduations 45 may indicate degrees or parts of degrees of circular measurement so that the pair of eccentrics 23, 26 can be readily adjusted with their high points at any desired number of degrees and fractions of degrees from the high points of the pair of eccentrics 24, 25. 115

120 The shaft 28 rotates in a bearing 46 of the frame 1 and may be provided with a 125

pulley 47, which is shown fragmentarily in Fig. 2, or other means whereby power may be readily applied to the shaft to operate the concentrator.

5 The eccentric straps 12, 19, 22 are seated in blocks 48 which are free to move horizontally between guides 49 in the form of wedges which rest on inclined faces 50 of the chambers 11, 18. The guides 49 may be 10 adjusted endwise to take up wear by turning screws 51. The guides 49 thus prevent vertical motion of the blocks 48.

15 The eccentric straps 20, 21 are seated in blocks 52 which are free to move vertically between guides 53, 54, the guides 53 being formed by certain vertical faces of the chambers 18 and the guides 54 by a wedge-shaped member resting against inclined faces 55 of the chambers 18. The guides 54 may be 20 adjusted endwise to take up wear by turning screws 56. The guides 54 thus prevent horizontal motion of the block 52.

25 From the foregoing it is clear that rotation of the eccentrics 13, 23, 26 causes horizontal motion of the blocks 48 relative to the arm 5 so as to be ineffectual to transmit horizontal motion to said arm and that said eccentrics operate to cause up and down motion of the arm and therefore of the table 30 2; and also that rotation of the eccentrics 24, 25 causes vertical motion of the blocks 52 relative to the arm 5 so as to be ineffectual to transmit vertical motion to said arm and that said eccentrics 24, 25 operate to cause 35 to and fro motion of the arm and therefore of the table.

40 The up and down motion caused by operation of the eccentrics 23, 26 corresponds in time with that caused by operation of the eccentrics 13.

The chambers 11, 18 may be provided, as shown, with cover plates 57 held in place by screws 58.

45 The foregoing described mechanism operates as follows: When the pulley 47 is driven through the agency of a belt or the like by any suitable power the eccentrics will all be turned as is obvious. Now refer to Fig. 7 in which *d* is the low point on the eccentrics and *h* the high point. First assuming that the pair of eccentrics 23, 26 is adjusted so that their high points are 45° of circular measurement from the high points of the pair of eccentrics 24, 25, that 50 the table 2 is at the lowest point *d*, that the direction of rotation of the shaft 28 is counter-clockwise as indicated by the arrow in said figure and that the table slopes, for instance, upward to the right, the movement 55 of every portion of the table surface will be in a slight curve forward and upward from *d* to *e* and thence from *e* to *f*. This movement corresponds to 90° of revolution of the shafts 16, 28 and one-half of the upward 60 stroke occurs while a relatively larger por-

tion of the horizontal stroke is made or, in other words, during the period of time of this movement the horizontal movement has a predominating effect on the material. The result of this movement is to give the material lying on the table a relatively quick forward and relatively slow upward impulse, the horizontal component of said impulse being the greater.

70 As the shafts 16, 28 revolve the eccentrics through another 45° the table is moved forward and upward from *f* to *g*, the vertical component relative to the horizontal component being much greater than the vertical component relative to the horizontal component during the movement from *d* to *f*.

75 Turning of the shafts 16, 28 through another 45° causes the table to move backward and upward from *g* to *h*. The movement from *f* to *h* gives the material on the table 80 a sudden upward impulse for a short period of time just prior to, during and subsequent to reversal of the horizontal stroke.

85 As the shafts 16, 28 rotate the eccentrics through another 90° of circular measurement the table moves backward and downward in the path *h*—*k*, but the material which has been given a forward and upward impulse, as noted above, continues its 90 forward and upward movement for an instant due to the inertia of said material and during this movement of the material the table moves away therefrom downward in the path *h*—*k* and consequently no frictional resistance exists between the table and 95 the material at the time of this reverse stroke.

100 Turning of the shafts through another 45° causes the table to move backward and downward in the path *k*—*m*, the backward movement being relatively slow and the downward movement being relatively quick.

105 The speed of the machine will be so regulated that the action of gravity will bring the material again in contact with the table surface at substantially the instant the table starts on its next forward stroke in the path *m*—*d*. During the latter part of its backward movement from *k* to *m* the table drops very rapidly relative to its backward motion and then drops more slowly from its reversal point *m* to its lowest position *d*.

110 When the table reaches the position *d* the material has fallen upon it and the table then starts slowly forward again to repeat 115 the cycle of movements as above described. As the table moves forward and downward slowly from *m* to *d* the material will again be put into motion by the table without undue friction of the material due to the inertia 120 thereof since its rearward motion has been stopped at least in part by the force of gravity acting on the ore particles from the time they are thrown from the table to the time of their alighting on the table.

The angular velocity of the shafts may be made such that the table surface will move from its highest position backward to its point of horizontal reversal while the 5 force of gravity, plus the upward fluid pressure of the air from the blower 3 through the perforated surface of the table, is overcoming the inertia of the material, the force of gravity acting through the vertical distance between the horizontal planes passing 10 through h , m , respectively.

The upward fluid pressure on the material will vary during the cycle of movements of each particle of the material due to the fact 15 that the bed of material covering the table surface and acting as a sort of blanket or a "buffer" is relatively traveling away from the table surface at one instant and toward it at another, thus relieving and increasing the pressure alternatively. Thus a 20 "puffing" effect is produced which is favorable to the rapid separation and stratification of the different classes of material according to the specific gravities of the particles constituting said material. This "puffing" effect has been heretofore attempted 25 in other ways by various more complicated and less efficient constructions.

In Fig. 7 the high points d^2 of the eccentrics 30 23, 26 are 45° in advance of the high points d' of the eccentrics 24, 25. Thus it is clear that the table is moved in an elliptical path, the major axis of the ellipse being oblique to the horizontal, and the 35 lowermost position of the table occurs subsequent to the beginning of the forward stroke and the highest position of the table occurs subsequent to the beginning of the back stroke.

40 The effect of the above described movements has been thoroughly tested on practically all kinds of ores and has proven very successful in the operation of obtaining concentrates.

45 In Figs. 7 to 10 different points in the path of movement of any given point on the table surface are indicated by letters and corresponding points on the eccentrics 24, 25 are indicated by the same letters primed 50 and corresponding points on the eccentrics 23, 26 are indicated by the same letters with the exponent "2."

Fig. 8 illustrates the path of movement 55 of the table produced by relatively adjusting the eccentrics so that the high points of the eccentrics 23, 26 are 90° in advance of the high points of the eccentrics 24, 25. By this adjustment, assuming that the eccentrics are being rotated in the direction of 60 the arrow, every portion of the table will move in an oblique path from its lowest position d to its highest position h and then rearward in the same path.

In Fig. 9 the eccentrics are adjusted so 65 that the high points of the eccentrics 23,

26 coincide with the high points of the eccentrics 24, 25 so that the movement of the table will be in an elliptical path, the major axis of the ellipse being horizontal.

In Fig. 10 is illustrated the movement of 70 the table in an elliptical path by adjusting the eccentrics so that the high points of the eccentrics 23, 26 are 45° behind or 315° in advance of the high points of the eccentrics 24, 25. In this instance the major axis of the 75 elliptical path is oblique to the horizontal and the lowermost position of the table occurs just before the end of the forward stroke of the table and the highest position occurs just prior to the end of the backward stroke 80 of the table.

In the drawings the eccentrics 24, 25 are shown larger than the eccentrics 23, 26 and it is understood that the relative sizes of the eccentrics may be as desired for obtaining 85 any degree of horizontal and vertical throw.

The invention is not limited to the adjustments of the eccentrics capable of producing the movements depicted in Figs. 7 to 90 10 for it is obvious that in practice it may be desirable to modify the movement of the table by other adjustments of the eccentrics; and it may be desirable at times to adjust the table so that it slopes downward toward 95 its discharge end.

From the foregoing it will be readily understood, that by setting the eccentrics so that the high points of the eccentrics 23, 26 are 135° behind the high points of the eccentrics 24, 25 and rotating said eccentrics opposite to that indicated by the arrow in Fig. 7, the same path of movement and direction 100 of said movement of the table will be traced as that shown in said figure. 105

If, as hereinbefore suggested, the arm be movably connected with the frame 1 by the well known link instead of the eccentric device, it is clear that the end of the table adjacent the eccentrics will be given the full motion of the eccentrics as above described, and that the intensity of such motion will gradually diminish toward the discharge end 110 of the table to zero at a point immediately above the link. In practice this operation is 115 also very effective in concentrating the ore.

It is clear from the foregoing that the table 2 and the arm 5 are moved in an endless path extending in a vertical plane, and that the movement is faster at some portions of 120 said path than at other portions thereof.

A new method is effected by the operation of the above described concentrator and such method consists in causing the ore to move away from a reciprocating supporting surface for an interval of time while the surface is moving in one direction so as to eliminate friction between the ore and the surface causing movement thereof. The method also consists in delivering a current air be- 125 130

neath the ore-supporting surface while the ore moves up and down so as to cause decreased air pressure beneath the ore when the ore moves up and to cause increased air 5 pressure beneath the ore when the ore falls toward the supporting surface. The method also consists in imparting alternative forward and backward motions to the ore, and overcoming in part the backward motion of 10 the particles by the aid of gravity while the particles are free from the impelling surface. The method furthermore consists also in directing a current of air upward beneath the particles to further aid in overcoming the 15 backward motion of the particles.

I claim:

1. In a dry ore concentrator, a table having a perforated ore-supporting surface, means to blow air upwardly through the 20 perforations, and means to move a portion of the table in an elliptical path.

2. In a dry ore concentrator, a table having a perforated ore-supporting surface, means to blow air upwardly through the 25 perforations, and means to move the table in an elliptical path.

3. In a dry ore concentrator, a table having a perforated ore-supporting surface, means to blow air upwardly through the 30 perforations, and means to move a portion of the table in an elliptical path, the major axis of the ellipse being oblique to the horizontal.

4. In a dry ore concentrator, a table having a perforated ore-supporting surface, means to blow air upwardly through the 35 perforations, and means to move a portion of the table in an elliptical path, the major axis of the ellipse being aslant upward toward the discharge end of the table.

5. In a dry ore concentrator, a table having a perforated ore-supporting surface, means to blow air upwardly through the 45 perforations, and means to impart relatively slow forward motion to the table and relatively quick upward motion near the end of the forward motion so as to throw material upward from the surface of the table.

6. In a dry ore concentrator, an arm, a 50 table mounted on said arm and having a perforated ore-supporting surface, means to blow air upwardly through the perforations, a frame, vertical and horizontal-motion devices connecting the frame to the arm, and means to operate said devices.

7. In a dry ore concentrator, an arm, a 55 table mounted to tilt transversely on said arm and having a perforated ore-supporting surface, means to blow air upwardly through the perforations, a frame, motion mechanism connecting the arm to the frame, and means to tilt the frame lengthwise.

8. In a dry ore concentrator, an arm, a 60 table mounted on said arm and having a perforated ore-supporting surface, means to

blow air upwardly through the perforations, a frame, a vertical-motion eccentric device and a horizontal-motion eccentric device connecting one end of the arm to the frame, means movably connecting the other 70 end of the arm to the frame, and means to drive the eccentric devices.

9. In a dry ore concentrator, an arm, a table mounted on said arm and having a perforated ore-supporting surface, means to 75 blow air upwardly through the perforations, a vertical-motion eccentric device connected to each end of the arm, a horizontal-motion device connected to one end of the arm, and means to drive the eccentric 80 devices.

10. In a dry ore concentrator, an arm, a table mounted on said arm and having a perforated ore-supporting surface, means to blow air upwardly through the perforations, a frame, a vertical-motion eccentric 85 device connecting one end of the arm to the frame, vertical and horizontal-motion devices connecting the other end of the arm to the frame, and means to drive the eccentric 90 devices.

11. In a dry ore concentrator, an arm, a table mounted on said arm and having a perforated ore-supporting surface, means to blow air upwardly through the perforations, vertical and horizontal-motion eccentric devices for operating one end of the 95 arm, means movably supporting the other end of the arm, and means for adjusting the vertical-motion eccentric device relative to 100 the horizontal-motion device to produce different motions of the arm.

12. In a dry ore concentrator, a table, an arm supporting the table, a frame, means movably connecting one end of the arm to the frame, a shaft journaled in the frame, an eccentric fast on the shaft, sleeves on the shaft, means to prevent relative rotation of the sleeves and shaft, an eccentric fast on one sleeve, a pair of eccentrics fast on the other 110 sleeve, blocks mounted in the arm shiftable only endwise thereof, other blocks mounted in the arm shiftable only vertically thereof, eccentric straps supported in the first named blocks for the first and second named eccentrics respectively, and eccentric straps supported in the second named blocks for the last named eccentrics respectively, the first and second named eccentrics having their high points at different circumferential positions than the high points of the last named eccentrics.

13. In a dry ore concentrator, a table, an arm supporting the table, a frame, means movably connecting one end of the arm to 115 the frame, a shaft journaled in the frame, two eccentrics mounted on the shaft to turn therewith, said eccentrics having their high points at different circumferential positions from one another, blocks mounted in the 120

130

other end of the arm, one of said blocks being shiftable only endwise of the arm and the other block being shiftable only vertically of the arm, and eccentric straps supported in the blocks for the eccentrics respectively.

14. In a dry ore concentrator, a table, an arm supporting the table, a frame, means movably connecting one end of the arm to the frame, a shaft journaled in the frame, two eccentrics mounted on the shaft, means to adjust one of the eccentrics relative to the other to change the circumferential relations to one another of the high points of the eccentrics, blocks mounted in the other end of the arm, one of said blocks being shiftable only endwise of the arm and the other block being shiftable only vertically of the arm, and eccentric straps supported in the blocks for the eccentrics respectively.

15. In a dry ore concentrator, a table, an arm supporting the table, a frame, means movably connecting one end of the arm to the frame, a shaft journaled in the frame, an eccentric fast on the shaft, sleeves on the shaft, an eccentric fast on one sleeve, a pair of eccentrics fast on the other sleeve, means to prevent relative rotation of the shaft and one of the sleeves, means to adjustably fix the other sleeve relative to the shaft, blocks mounted in the other end of the arm, a pair of said blocks being shiftable only endwise of the arm and a pair of said blocks being shiftable only vertically of the arm, and eccentric straps supported in the blocks respectively for the respective eccentrics.

16. In a dry ore concentrator, a table, an arm supporting the table, a frame, shafts journaled in the frame, an eccentric on one of said shafts, a block mounted in one end of the arm and shiftable only endwise thereof, an eccentric strap mounted in the block for said eccentric, eccentrics mounted on the other shaft to turn therewith, blocks mounted in the other end of the arm, one of said last named blocks being shiftable only endwise of the arm and the other of the last named blocks being shiftable only vertically of the arm, eccentric straps supported in the last named blocks respectively for the respective last named eccentrics, and means operatively connecting the shafts to one another.

17. In a dry ore concentrator, a table, an arm supporting the table, a frame, shafts journaled in the frame, an eccentric on one of said shafts, a block mounted on one end of the arm and shiftable only endwise thereof, an eccentric strap mounted in the block for said eccentric, an eccentric fast on the other shaft, sleeves on the other shaft, an eccentric fast on one sleeve, a pair of eccentrics fast on the other sleeve, means to prevent relative rotation of the shaft and one of the sleeves, means to adjustably fix the

other sleeve relative to the shaft, blocks mounted in the other end of the arm, a pair of said last named blocks being shiftable only endwise of the arm and a pair of said last named blocks being shiftable only vertically of the arm, eccentric straps supported in the last named blocks respectively for the eccentrics on the other shaft and on the sleeves respectively, and means operatively connecting the shafts to one another.

18. In a dry ore concentrator, a table having a perforated ore-supporting surface, means to blow air upwardly through the perforations, and means to move the table in an endless path extending in a vertical plane.

19. In a dry ore concentrator, a table having a perforated ore-supporting surface, means to blow air upwardly through the perforations, and means to move the table in an endless path extending in a vertical plane, the movement being faster at some portions of said path than at other portions thereof.

20. In combination, an arm, a frame, means movably connecting one end of the arm to the frame, a shaft journaled in the frame, an eccentric fast on the shaft, sleeves on the shaft, means to prevent relative rotation of the sleeves and shaft, an eccentric fast on one sleeve, a pair of eccentrics fast on the other sleeve, blocks mounted in the arm shiftable only endwise thereof, other blocks mounted in the arm shiftable only vertically thereof, eccentric straps supported in the first named blocks for the first and second named eccentrics respectively, and eccentric straps supported in the second named blocks for the last named eccentrics respectively, the first and second named eccentrics having their high points at different circumferential positions than the high points of the last named eccentrics.

21. In combination, an arm, a frame, means movably connecting one end of the arm to the frame, a shaft journaled in the frame, two eccentrics mounted on the shaft to turn therewith, said eccentrics having their high points at different circumferential positions from one another, blocks mounted in the other end of the arm, one of said blocks being shiftable only endwise of the arm and the other block being shiftable only vertically of the arm, and eccentric straps supported in the blocks for the eccentrics respectively.

22. In combination, an arm, a frame, means movably connecting one end of the arm to the frame, a shaft journaled in the frame, two eccentrics mounted on the shaft, means to adjust one of the eccentrics relative to the other to change the circumferential relations to one another of the high points of the eccentrics, blocks mounted in the other end of the arm, one of said blocks

being shiftable only endwise of the arm and the other block being shiftable only vertically of the arm and eccentric straps supported in the blocks for the eccentrics respectively.

23. In combination, an arm, a frame, means movably connecting one end of the arm to the frame, a shaft journaled in the frame, an eccentric fast on the shaft, sleeves on the shaft, an eccentric fast on one sleeve, a pair of eccentrics fast on the other sleeve, means to prevent relative rotation of the shaft and one of the sleeves, means to adjustably fix the other sleeve relative to the shaft, blocks mounted in the other end of the arm, a pair of said blocks being shiftable only endwise of the arm and a pair of said blocks being shiftable only vertically of the arm, and eccentric straps supported in the blocks respectively for the respective eccentrics.

24. In combination, an arm, a frame, shafts journaled in the frame, an eccentric on one of said shafts, a block mounted in one end of the arm and shiftable only endwise thereof, an eccentric strap mounted in the block for said eccentric, eccentrics mounted on the other shaft to turn therewith, blocks mounted in the other end of the arm, one of said last named blocks being shiftable only endwise of the arm and the other of the last named blocks being shiftable only vertically of the arm, eccentric straps supported in the last named blocks respectively for the respective last named eccentrics, and means operatively connecting the shafts to one another.

25. In combination, an arm, a frame, shafts journaled in the frame, an eccentric on one of said shafts, a block mounted on one end of the arm and shiftable only endwise thereof, an eccentric strap mounted in the block for said eccentric, an eccentric fast on the other shaft, sleeves on the other shaft, an eccentric fast on one sleeve, a pair of eccentrics fast on the other sleeve, means to prevent relative rotation of the shaft and one of the sleeves, means to adjustably fix the other sleeve relative to the shaft, blocks mounted in the other end of the arm, a pair of said last named blocks being shiftable only endwise of the arm and a pair of said last named blocks being shiftable only vertically of the arm, eccentric straps supported in the last named blocks respectively for the eccentrics on the other shaft and on the sleeves respectively, and means operatively connecting the shafts to one another.

26. In a dry ore concentrator, a table having its discharge end higher than its intake end and having a perforated ore - support-

ing surface; means to blow air upwardly through the perforations, and means to move a portion of the table in an elliptical path.

65

27. In a dry ore concentrator, a table having a perforated ore supporting surface, means to blow air upwardly through the perforations, and means to toss the particles of ore toward the discharge end of the table.

70

28. In a dry ore concentrator, a table having its discharge end higher than its intake end and having a perforated ore - supporting surface, means to blow air upwardly through the perforations, and means to toss the particles of ore toward the discharge end of the table.

75

29. In a dry ore concentrator, a table, and means to move a portion of the table in an elliptical path, the movement near the finish of the forward stroke being accelerated upwardly.

80

30. In a dry ore concentrator, a table having its discharge end higher than its intake end, and means to move a portion of the table in an elliptical path, the movement near the finish of the forward stroke being accelerated upwardly.

85

31. In a dry ore concentrator, a table having a perforated ore-supporting surface, means to blow air upwardly through the perforations, and means to move a portion of the table in an elliptical path, the movement near the finish of the forward stroke being accelerated upwardly.

90

32. In a dry ore concentrator, a table having its discharge end higher than its intake end and having a perforated ore - supporting surface, means to blow air upwardly through the perforations, and means to move a portion of the table in an elliptical path, the movement near the finish of the forward stroke being accelerated upwardly.

100

33. In a dry ore concentrator, a table, and means to move a portion of the table forwardly with a final upward rapidly accelerating movement so as to toss the material free of the table, said means returning the table while the material is in suspension.

105

34. In a dry ore concentrator, a table, and means to move a portion of the table forwardly with a final upward rapidly accelerating movement so as to toss the material free of the table, said means returning the table rearwardly and downwardly while the material is in suspension.

Certificate of Correction.

It is hereby certified that in Letters Patent No. 1,397,749, granted November 22, 1921, upon the application of Alva W. Tyler, of Los Angeles, California, for an improvement in "Concentrators," errors appear requiring correction as follows: In the drawings, Sheets 1 and 2, in headings, line 5, for "2 Sheets" read *3 Sheets*; Sheet 3, containing Figures 11 to 14, inclusive, should appear as shown below as part of the Letters Patent:

Fig. 11

Fig. 12

Fig. 13

Fig. 14

INVENTOR.
BY *Alva W. Tyler.*
Endriss, Bryan
atty

and that the said Letters Patent should be read with these corrections therein that the same may conform to the record of the case in the Patent Office.

Signed and sealed this 7th day of February, A. D., 1922.

[SEAL.]

KARL FENNING,
Acting Commissioner of Patents.
